UNITED STATES PATENT OFFICE.

FRANK ANTONUCCIO, OF STOCKTON, CALIFORNIA.

WATER-HEATER.

1,090,512.

Specification of Letters Patent. Patented Mar. 17, 1914.

Application filed December 27, 1912. Serial No. 738,811.

To all whom it may concern:

Be it known that I, FRANK ANTONUCCIO, citizen of the United States, residing at Stockton, in the county of San Joaquin and

5 State of California, have invented certain new and useful Improvements in Water-Heaters, of which the following is a specification.

The present invention relates to certain 10 new and useful improvements in hot water heaters, and has for its object to provide a device of this character which embodies novel features of construction whereby the 15 water in a tank or boiler can be quickly and economically heated by means of a gas burner.

A further object of the invention is to provide a water heater of this character which is comparatively simple and inexpensive 20 in its construction, which comprises few and durable parts which can be readily taken apart or assembled, and which provides a large heating surface for the water.

With these and other objects in view, the 25 invention consists in certain novel combinations and arrangements of the parts as will more fully appear as the description proceeds, the novel features thereof being pointed out in the appended claims.

30 For a full understanding of the invention, reference is to be had to the following description and accompanying drawing, in which:—

Figure 1 is a vertical sectional view 35 through a hot water heater constructed in accordance with the invention. Fig. 2 is a side elevation of the upper heating drum. Fig. 3 is a similar view of the lower heating drum, and Fig. 4 is an enlarged sectional view through the burner.

Corresponding and like parts are referred to in the following description and indicated in all the views of the drawings by the same reference characters.

45 Specifically describing the present embodiment of the invention, the numeral 1 designates a tank or boiler which is arranged in an upright position and supported upon a suitable stand 2. This boiler is 50 provided at the top thereof with an outlet pipe 3 through which the hot water can be withdrawn from the boiler, and also with an inlet pipe 4 which serves to convey cold water to the boiler and extends downwardly 55 within the boiler to a point toward the bot-

tom thereof so that the cold water is prevented from mixing directly with the hot water which may have accumulated at the top of the boiler.

The bottom 5 of the boiler has a substantially bell shaped construction and projects upwardly within the boiler so as to provide a large heating surface for the water. The upper end of the hollow or bell shaped bottom 5 communicates through an offset member 6 with an exhaust pipe 7 which extends upwardly through the top of the boiler.

The burner 8 is arranged within the lower portion of the hollow or bell shaped bottom 4 and the products of combustion passing 70 through the offset 6 and exhaust pipe 7 will serve to heat the said members so as to aid in heating the water which is in direct contact therewith. This burner 8 is connected with a gas supply pipe 9 and a pilot 10 is 75 provided for convenience in lighting the burner. The burner plate 8^a is of peculiar construction, being formed with the gas outlet openings 11 and the annular pockets 12, the said annular pockets serving to collect 80 any moisture or drippings due to sweating of the pipes or heating drums so as to prevent the moisture from entering the interior of the burner and interfering with the proper operation thereof.

An upper heating drum A and a lower heating drum B are arranged within the hollow or bell shaped bottom 5 and disposed above the burner 8, so as to be acted upon by the same. These two heating drums are 90 connected by a pipe 13, the top of the upper heating drum A being connected to and in communication with a circulation pipe 14 which extends upwardly into the boiler and toward the top thereof, while the bottom of 95 the lower drum B is connected to and in communication with a vertical pipe 15 which extends downwardly through the central opening 16 of the burner 8 and communicates with a lateral supply pipe 17 extending through the side of the bell shaped bottom 5 and communicating with the interior of the boiler 1. The various pipes 14, 13, and 15 are all vertically disposed and in substantial alignment with each other and the cooler water enters the lower drum B of the boiler 1 and as it becomes heated within the drums A and B circulates upwardly and finally passes through the upper pipe 14 to the top of the boiler. In this way a circula- 110

tion of water is automatically provided within the boiler as long as the burner 8 remains lighted.

With regard to the upper circulation pipe 14 it will be observed that this pipe is fitted within a bushing 18 which extends through and is threaded within an opening in the offset member 6, the said bushing and pipe preferably being arranged substantially at 10 the vertical axis of the boiler.

The lower heating drum B is preferably an integral member so as to avoid the necessity for a multiplicity of joints which would be liable to cause leakage. This lower 15 heating drum B is formed with a series of laterally curved and substantially semicircular arms or passages 19 which are arranged in vertical planes radiating from the axis of the drum, the said arms establishing 20 communication between the top and bottom of the drum which are spaced from each other to admit of the products of combustion and hot air circulating freely around the curved arms and between the top and bottom 25 of the drum. At the bottom of the drum where the lower ends of the several curved arms meet the drum is connected to the lower vertical pipe 15, while at the top of the drum where the upper ends of the several curved arms 19 meet, connection is made 30 with the pipe 13 which leads to the upper drum A. This upper drum A comprises a substantially hemispherical top 20, the bottom thereof being formed with a downwardly facing pocket 21 which serves to 35 catch and collect the heated products of combustion rising from the burner. A series of quadrants or arms 22 which are arranged in vertical planes radiating from the axis of 40 the drum serve to connect edge portions of the top 20 with the bottom of the drum where the said quadrants or arms 22 meet and the drum is connected to the pipe 13. With this construction the products of 45 combustion can circulate freely around the curved arms 22 and the upper and lower surfaces of the top 20 of the drum so as to heat the water within the same.

In the operation of the heater, it will be 50 obvious that when the burner 8 is lighted, the heat therefrom will act, as before mentioned, to heat the hollow bottom 5 and the

exhaust pipe 7, and will also act upon the upper and lower heating drums A and B to heat the water within the same. Owing to 55 the exceptionally large heating surface provided by the peculiar construction of these upper and lower heating drums, the water therein will be thoroughly and quickly heated so as to rise through the pipe 14 to the 60 top of the boiler 1. The hot water which thus enters the top of the boiler from the heating drums is replaced by cooler water which enters the lower drum B through the lateral pipe 17 and lower vertical pipe 15. 65

Having thus described the invention, what I claim as new and desire to secure by Letters Patent, is:—

1. In a water heater, a heating drum including an upper hollow and substantially 70 hemispherical head having a convex upper surface and a concave lower surface, the latter providing a closed downwardly facing pocket, a lower head arranged axially under the upper head, a series of vertically disposed and substantially quadrant shaped 75 curved arms connecting the edges of the upper head to the lower head, the arms having flat outer and inner faces which are continuations of the curvature of the corresponding surfaces of the upper head, and axially disposed circulation pipes connected to the upper head and lower head respectively. 80

2. A water heater including a boiler formed with a concave bottom, an offset 85 member communicating with the top of the concave bottom, a flue extending from the offset member through the top of the boiler, a bushing extending through the offset member and arranged substantially axially with 90 respect to the lower end thereof, a circulation pipe extending through the bushing and fitting tightly therein, a heating drum arranged within the hollow bottom of the boiler and connected with the circulation pipe, and a burner, the products of combustion 95 from the burner escaping through the offset and flue.

In testimony whereof I affix my signature in presence of two witnesses.

FRANK ANTONUCCIO.
